PROCESS AND APPARATUS FOR RECOVERING AND PROCESSING BY-PRODUCTS AT A COAL DISTILLATION PLANT

Stuart Parmelee Miller, Englewood, N. J., assignor to The Barrett Company, New York, N. Y., a corporation of New Jersey

Application June 14, 1929, Serial No. 370,954

7 Claims. (CL 202—30)

This invention relates to the recovering and processing of by-products at a coal distillation plant, such as a coke oven plant. It includes both the process and apparatus for carrying it out.

5 According to the usual operation of a coke oven battery, the gases leaving the ovens are collected in a gas-collector main and partially cooled therein. The cooling of the gases causes higher boiling resins or pitches and oils to separate from 10 the gases together with a portion of the entrained solid impurities carried from the ovens by the gases. These ingredients constitute a heavy tar. After leaving the collector main the partially cooled gases are further cooled and a tarry oil 15 separates, which comprises oils of lower boiling range and at least a portion of the impurities remaining in the gases. This product is herein referred to as a light tar or tarry oil. The heavy tar from the collector main is a heavier product 20 than the tarry oil and contains oils of higher boiling range and a lower proportion of oils of lower boiling range. The tarry oil is relatively rich in tar acids and ordinarily has a relatively high naphthalene content. It is customary to blend 25 the heavy tar and tarry oil and where clean oil distillates are desired, the total tar thus produced is ordinarily shipped to a tar distillation plant to be distilled.

According to this invention the hot coal distillation gases from a coal distillation plant are fractionally cooled to separate tar fractions comprising oils of different boiling ranges, and these different tar fractions are differently treated. The heavy tar from the collector main of a coke 35 oven plant and the tarry oils from the condensers, for example, may be separately collected and not blended, as in the usual methods of procedure, but separately and differently treated. According to the invention, a heavy tar fraction such as 40 the heavy tar from the collector main is distilled. The distillation is controlled so as to produce a desired oil product or a desired pitch, either of which may be used directly or after blending with tar such as the light tar or tarry oil from the 45 condensers.

The heavy tar predominates in higher boiling oils and has a relatively lower percentage of oils of lower boiling range as compared with the tarry oil from the condensers or the total tar produced 50 by blending the various tar fractions in accordance with the usual practice. On distilling the heavy tar a distillate comprising oils of relatively higher boiling range will be obtained and this distillate will have a relatively low tar acid 55 content and will be relatively poor in naphtha-

lene. Clean oil distillates of higher and lower boiling range may be obtained by fractionally recovering the distillate from the heavy tar. The clean oil of higher boiling range will have a still lower content of tar acid and also less naphthalene. On the other hand, the clean oil distillate of lower boiling range will if well fractionated contain more naphthalene and may be relatively rich in tar acids. The distillate, preferably the lower boiling distillate fraction, may be extracted 60 to recover tar acids. The resulting neutral oil may be used in preparing creosoting composition or it may be blended with pitch resulting from the distillation of the tar and burned for fuel. Where only the lower boiling fraction of distillate is extracted for tar acids, the neutral oil obtained may be blended with the higher boiling distillate fraction and the blended mixture used 65 as clean creosote oil. The preparation of clean creosote oil in this manner is particularly applicable to the treatment of distillate resulting from the distillation of the heavy tar to a high melting point pitch, for example, pitch with a melting point of 350 or 400° F. Where constituents of 70 high boiling point are distilled from the tar and it is desirable to blend these with oils of lower boiling range in preparing an oil suitable for creosoting, the neutral oil above referred to may be used as the oil of lower boiling range.

For some purposes tar products containing a 75 small amount of free carbon may be desirable. In the manufacture of creosoting compositions of the so-called coal tar solution type, for example, a small amount of free carbon, for example, up to 2 or 3% of free carbon, is permissible. According 80 to this invention, the distillate from the heavy tar may be blended with other heavy tar or with tarry oil or total tar to produce creosoting composition. Creosoting composition is ordinarily prepared by blending a certain amount of distillate from total tar with a small amount of total tar, for example, 80% of distillate may be 85 blended with 20% of total tar. According to the method of this invention, the heavy tar distillate may be blended with tarry oil to produce creosoting composition. Owing to the fact that the tarry oil contains a smaller percent of free carbon and predominates in oils of lower boiling range than ordinary total tar, a larger percentage 90 of tarry oil may be blended with the distillate to produce creosoting composition than the percentage of total tar ordinarily employed for blending.

The heavy tar may be distilled to pitch of higher or lower melting point. When creosoting com- 110

position is to be prepared from the distillate and oils of higher boiling range are desired in the creosoting composition, a pitch of high melting point, e. g. in the neighborhood of 350° F. or over, 5 will be prepared in order to throw oils of higher boiling range over into the distillate. The pitch produced may be utilized as such, for example as a briquette pitch, when the melting point is approximately 185° F. or the pitch may be blended 10 with heavy tar or tarry oil or total tar from another plant and be used as fuel.

A pitch of a high melting point or relatively high melting point may readily be blended with the tar by mixing the pitch with the tar while 15 hot. A stream of the tar and hot pitch from separate nozzles may be directed toward one another on entering a mixing tank in such a way that before the streams of pitch and tar reach the blended mixture in the mixing tank, considerable 20 mixing has taken place. By heating the tank as with steam coils, and agitating the tar and pitch within the tank, where necessary, and also heating the tar where necessary, a homogeneous 25 mixture well suited for use as fuel may be obtained. By regulating the temperature, a thinly fluid fuel may be produced. It may be desirable to enclose the mixing chamber and equip it with a reflux condenser to prevent the escape of oil 30 vapors to the atmosphere.

The method of this invention may readily be carried out at an ordinary coke oven plant without extensive alteration of the by-product recovery system. The invention may, for example, be carried on in connection with a Semet-Solvay 35 plant, or at a Koppers plant by providing separate means for the recovery of heavy tar and tarry oil, and means for distilling the heavy tar.

The invention will be further described in connection with the accompanying drawings, but it is intended and is to be understood that it is not limited thereto.

In the drawings—

Fig. 1 is a plan view of apparatus for carrying out the invention;

Fig. 2 is an elevation partly in section of the apparatus of Fig. 1; and

Fig. 3 is a section of the still taken on line 3—3 of Fig. 2.

The battery of coke ovens 5 is provided with a 50 collector main 6 which connects with each of the ovens thru uptake pipes and goose-necks 7. A cross-over main 8 connects with the condensers 9 and 10 and an exhauster 11 is provided for drawing the gases thru the system.

Where the battery is of the Semet-Solvay type 55 in which the gases are sprayed with ammonia liquor in the collector main, means for spraying the gases in the collector main are provided and the gases may also be sprayed in the goose-necks.

The gases are thereby cooled and the heavy oils 60 separated from the gases carry with them entrained impurities. The heavy tar thus produced is withdrawn from the collector main together with unvolatilized ammonia liquor into the de- 65 canter 12. Heavy tar is separated into the tank 13.

According to a common method of operating a coke oven battery of the Koppers type, tar and ammonia liquor which separate from the collector 70 main and tar and ammonia liquor from the condensers are collected in a common storage tank and a mixture of this tar and ammonia liquor is circulated thru the collector main. This cools the gases in the collector main and higher boiling 75 oils separate from the gases dissolving in the tar

and carrying with them entrained impurities. The heavy tar from the collector main and tarry oil from the condensers are not ordinarily collected separately. The present invention, however, contemplates separate collection of heavy and light tars and the operation of the collector main must be modified to meet these conditions.

Where the invention is carried out at a plant comprising ovens connected with more than one collector main, a mixture of the tar and the tarry oil from one or more other collector mains and condensers may be used for flushing the collector main 6 to prevent the accumulation of pitch therein. This flushing of the main will cool the gases, and cause the separation of heavier oils 80 from the gases. A heavy tar will result, the oils in which will predominate in higher boiling constituents which separate from the gases in the collector main. A portion of this tar may be recirculated thru the collector main. The balance may be kept separate from the tarry oil 85 separated in the condensers. It may be run to a storage tank, such as 13, for further treatment.

Where the ovens connected with the collector main 6 are to be operated as a separate unit, i. e. 90 where the gases in the collector main are not to be cooled with tar and ammonia liquor derived from the gases from other coke ovens, the heavy tar which separates in the collector main may be recirculated thru the collector main to flush the 95 main and to cool the gases and condense heavier oils to produce further heavy tar. Instead of recirculating heavy tar from the collector main back thru the collector main alone, it may be blended with tarry oil or ammonia liquor and tarry oil 100 from the condensers and the blended mixture may then be employed for flushing the main and cooling the gases in the collector main to separate the 105 heavy oils therefrom.

Tar from another source, which may be gas- 115 house tar, or even water gas tar, may be supplied to the collector main 6 and caused to flow thru the main to prevent the accumulation of deposits of pitch, and a portion of the heavy tar drawn off from the collector main may be recirculated with 120 this tar. Where the main is operated at high temperatures, as where no ammonia liquor is supplied to the main, or where the amount of ammonia liquor is limited, there may be some distillation of tar within the main.

Where tar or tar ammonia liquor are circulated 125 merely thru the bottom of the main to prevent the accumulation of pitch deposits, the gases may be sprayed at least to some extent with ammonia liquor to cool the gases and separate oils therefrom and such cooling may be regulated to provide for controlling the amount and character of the tar recovered from the main.

The cooling in the collector main may be regulated to control the boiling range of the oils condensed in the collector main. Such regulation simultaneously controls the boiling range of the tarry oils condensed in the condensers. By reducing the amount of ammonia liquor sprayed into the gases in the collector main, for example, the 130 reduction in the temperature of the gases in the collector main will be less and consequently the gases will leave the main at a higher temperature and will carry with them a higher percentage of oils, especially oils of higher boiling range. On 145 cooling these gases a heavy tarry oil will be obtained from the condensers and this tarry oil will contain a relatively high percent of oils of high boiling range. On the other hand, by increasing the extent to which the gases are cooled in the 150

- collector main, a tar will be obtained from the collector main which will contain a higher percentage of lower boiling oils, and the tarry oils from the condensers will comprise oils of relatively 5 lower boiling range than usual. By combined control of the cooling to which the gases are subjected in the collector main and the subsequent distillation of the heavy tar from the collector main, various distillate oils and pitches may be 10 produced from this heavy tar.
- Various types of stills may be employed for distilling the heavy tar. A pipe coil still may be utilized in which the tar is heated and the heated tar may then be passed to a vapor box in which 15 vapors resulting from the heating of the tar separate from the residue. On cooling the vapors a clean oil distillate will be obtained. Vacuum may be employed on the vapor chamber to aid in the distillation.
- 20 According to the preferred method of carrying out the invention, the heavy tar is distilled by bringing it into direct contact with hot coke oven gases or by combined direct and indirect contact as disclosed below.
- 25 The still 20 is preferably located at the side of the coke oven battery opposite the usual collection oven. Hot gases from selected ovens of the battery pass thru the uptake pipes and goose-necks 21 into the header 22. By the proper manipulation of valves in the uptake pipes and goose-necks 7 and 21, the gases from the ovens connected with the hot gas header 22 may be diverted either to the collector main 6 or to this header 22. The gases passing thru the uptake pipes 21 and hot gas header 22 into the still 20 are brought into 30 direct contact with an intense spray of tar within the still 20.
- 35 The still is provided with agitating means. This comprises the roll 23 which is located at one side 40 of the still and so situated that it dips to a slight extent into a body of the tar or partly distilled tar which is maintained in the bottom of the still. The roll is adapted to be rotated at a speed of 900—1200 R. P. M. by the motor 24. The tar to be distilled may be fed to the still thru the pipe 45 or preferably thru the pipe 26 which leads into the tower 27 thru which the gases and vapors leave the still. The tar sprayed into the tower thru pipe 26 in passing down thru the tower in direct 50 contact with the gases and vapors is heated and caused to approach equilibrium with the rising gases. Baffles 29 are provided below the nozzle 30 in order to expose a large surface of the tar to the action of the gases and thus to facilitate heat exchange between the gases and the tar. Baffles 28 may be provided above the nozzle 30 to assist in removing entrained material from the gases. The tar which collects in the bottom of the tower is preferably drawn off thru the pipe 55 31 and admitted to the still at the opposite end of the still so that the tar and the gases pass thru the still in concurrent direction, the gas inlet at the bottom of the tower being so designed as to prevent downward flow of tar thru it into the still. Where pitch of high melting point, e. g. pitch with a melting point in the neighborhood of 350° or 400° F. is to be produced, this concurrent flow of tar and gases is desirable. Where lower melting point pitch is to be produced, countercurrent flow of tar and pitch may 60 be used. In such a case tar sprayed into the tower may drain down into the still thru the gas connection between the still and the tower, and the pitch outlet will then be situated at the opposite end of the still.
- 75 The pitch produced is withdrawn from the still thru the tar trap 32 and the levelling arm 33. By regulating the position of the levelling arm, the amount of partially distilled tar or pitch retained in the still may be controlled and thus the extent to which the roll 23 dips into the pitch is regulated. The pitch may be granulated by chilling with cold water, or it may be flaked, or treated in any desired manner. It may be drawn off into the mixing tank 34 and mixed with tar for fuel or to produce pitches or for other purposes.
- 80 The tar for blending with the pitch is supplied thru the line 35. It may be tarry oil from the condensers or heavy tar from the collector main, or tar from other sources. The tar from 35 and pitch from 33 enter the tank in such a way that after they leave the lines thru which they are conveyed to the tank and before they reach the level of blended material within the tank, they are mixed to a considerable extent as they fall into the tank. The tank may be provided with agitating means. A steam coil 37 is shown for use when required to maintain the contents of the tank 34 in a thinly fluid and homogeneous condition. The levelling arm 33 and tank 34, etc. 90 may advantageously be enclosed and a reflux condenser 38 provided. Any condensate from the condenser may be returned to the tank 34, or recovered as a separate product.
- 95 The still is distilled in the still. The tar from the tank 13 may be pumped directly into the still or it may advantageously be brought into indirect contact with the hot gases and vapors leaving the still before being brought into direct contact with the gases in the still. In the former case the gas inlet at the bottom of the tower is so designed as to allow any reflux formed in the tower to reflux into the still. The gases and vapors leave the still thru the tower 27 and the main 40. They pass thru the heat interchanger 41, thru the main 42 100 into the condenser 43, and thence to an exhauster, which may be the exhauster 11.
- 105 According to the preferred method of operation, heavy tar from the collector main is pumped from the tank 13 by the pump 44 thru the line 45 into the pipe coil 46 within the heat interchanger 41. The gases and vapors within the heat interchanger are cooled and a clean oil of relatively 110 high boiling range is drawn off from this heat interchanger into the tank 47. The tar heated in 115 the heat interchanger is passed thru the line 48 into the vapor chamber 49 where partial distillation occurs. The vapors are drawn off thru the main 50 into the condenser 51 where clean oils of relatively low boiling range are condensed and 120 separately collected in the tank 52. The pitch residue is fed to the still preferably thru the tower 27 by means of the pump 53', the line 26 and the nozzle 30.
- 125 The tar is fed from the bottom of the tower 135 thru the line 31 into the still 20 and is there brought into direct contact with the hot gases coming from the hot gas header 22. The spray of tar thrown up into the gases by the roll 23 is so intense that the gases are scrubbed and substantially de-tarred, i. e., entrained impurities are removed from the gases so that the gases and vapors leaving the still thru the tower 27 are substantially free from entrained impurities. These gases and vapors pass to the heat interchanger 41 140 where heavier oils are separated and then to the condenser 43 where the remaining oils separate from the gases and are collected in the tank 53.
- 145 By first distilling the tar by indirect contact with the hot gases and vapors before bringing it 150

into direct contact with the gases, the lighter oils are distilled from the tar and separately collected and the hot gases passing thru the still are enriched only in higher boiling constituents. These 6 higher boiling constituents may readily be recovered from the gases, whereas lower boiling constituents which are first removed from the tar in the vapor box 49 and separately collected in the clean oil receiver 52 could be separated from the 10 gases only with difficulty, especially where oils of low boiling range were present, owing to the necessity for cooling the gases to much lower temperatures than required if only the heavy oils are present.

15 The pitch produced by distillation of this heavy tar is withdrawn thru the levelling arm 33 into the mixing tank 34. It may be blended with tar and also clean oil if desired and disposed of as desired.

20 Clean oils of lowest boiling range are collected in the tank 52; oils of higher boiling range are collected in the tank 53; and oils of high boiling range are collected in the tank 47. These are all clean oil distillates. The lower boiling distillate 25 or the two lower boiling distillates may be extracted for tar acids. The distillate may be extracted by any of the usual methods of extracting tar acids from coal tar distillate. A ten percent solution of caustic soda or other suitable 30 alkaline aqueous solution may be employed. The resulting neutral oil may be blended with higher boiling distillate and this combined clean oil product may be blended with tar recovered directly from the hot coke oven gases, as, for example, 35 tarry oil from the tank 15 or heavy tar from the tank 13 to produce creosoting composition. Clean distillate oil may be used directly for creosoting composition without first being extracted to remove tar acids, as, for example, where a single distillate fraction of relatively low tar acid 40 content is produced. The clean oils are low in naphthalene. The process of blending to produce coal tar solution is dependent upon the product desired. Where a product of low naphthalene 45 content is desired, heavy tar from the collector main may be preferred to tarry oil from the condensers as a blending material.

The three clean oil products may be blended and used for creosoting or one or two of the low- 50 boiling fractions may be first extracted for tar acids and the remaining neutral oil may be blended with the higher boiling distillate to produce clean creosote oil.

Where clean oil is extracted to remove tar acids 55 for tar acid recovery, the remaining neutral oil may be blended with the other tar and pitch ingredients in the mixing tank 34 and burned as fuel. It may be fed to the mixing tank thru the pipe 54.

60 By keeping the vapor chamber 49 under a vacuum a larger percentage of oils will distill from the tar in the vapor chamber than when the distillation is carried out under atmospheric pressure. The vacuum pump may advantageously be connected to the drain between the condenser 51 and the storage tank 52. When the vapor chamber is operated under a vacuum, the line 26 is preferably connected with the pitch receiver rather than directly with the draw-off from the vapor chamber 49. The pitch receiver and the distillate storage receiver 52 may advantageously be connected with the vapor chamber 49 and the condenser 51, respectively, thru barometric columns. By operating the vacuum chamber 65 under a vacuum, a larger percentage of oils in-

cluding higher boiling oils may be distilled from the tar heated in the coil 46 in the condenser 41, or the same quantity of lower boiling oils may be distilled in the vapor chamber with less preheating in the coil 46.

80 Although the invention has been described more particularly as applied to the treatment of hot coke oven gases, it comprises the treatment of other hot coal distillation gases. The gases are fractionally cooled to produce a heavy tar and a lighter tar or tarry oil. The heavy tar is distilled to pitch. The pitch produced may be blended with tar for fuel, etc. and the clean distillate oils may be variously used, as for the preparation of tar acids or creosoting composition or clean 85 creosote oil, etc.

90 This application is in part a continuation of my copending application Serial No. 316,894, filed November 3, 1928.

95 I claim:

1. The method of producing a heavy tar and treating the same, which comprises collecting the coal distillation gases from a plurality of the coke ovens of a coke oven plant in a gas-collector main, cooling these gases to separate a 100 heavy tar, separately collecting the heavy tar and distilling it in two stages, the second stage comprising bringing the residue from the first stage into direct contact with hot coke oven gases from the plant and the first stage comprising bringing the tar into indirect contact with hot gases and vapors resulting from the second stage of the distillation and then flashing the heated tar.

2. The method of producing a heavy tar and treating the same, which comprises collecting the 110 coal distillation gases from a plurality of the coke ovens of a coke oven plant in a gas-collector main, cooling these gases to separate a heavy tar, separately collecting the heavy tar and distilling it in two stages, the second stage comprising bringing the residue from the first stage into direct contact with hot coke oven gases from the plant and the first stage comprising heating the tar by indirect contact with hot gases and vapors resulting from the second stage and flashing vapors 115 from the heated tar in a vapor box maintained under a vacuum.

3. The method of producing a heavy tar and treating the same, which comprises collecting the coal distillation gases from a plurality of the coke ovens of a coke oven plant in a gas-collector main, partly cooling these gases to separate a heavy tar, separately collecting it, distilling the heavy tar to high melting point pitch, and obtaining two clean oil distillate fractions, extracting the lower boiling fraction to obtain tar 125 acids, and blending the resulting neutral oil with the higher boiling clean oil fraction.

4. In connection with a coke oven battery, a gas collector main, means for cooling the gases 130 in the main to produce a heavy tar, a condensing system for cooling the resulting gases to separate tarry oil therefrom, receivers connected with the collector main and condensing system for the heavy tar and the tarry oil respectively, a still, 140 means for conveying hot gases from selected ovens to the still, the only feeding means to the still being a pipe for conveying the heavy tar from the heavy tar receiver to the still, an agitator within the still for spraying the tar up into the gases and thereby substantially detarring the gases, and condensers for separating oils from the gases and vapors leaving the still.

5. A coke oven plant, a gas collector main connected with the ovens of the plant, means for 145

- subjecting the gases in the collector main to regulated cooling to separate a heavy tar from the gases in the collector main, a condenser for cooling the gases leaving the collector main and separating tarry oil therefrom, separate receivers connected with the collector main and condenser for the tarry oil and heavy tar respectively, a still, means for conveying gases from selected ovens into the still, atomizing means within the still whereby an intense spray of tar may be thrown up into the gases from the bottom of the still, a heat interchanger, a main to convey gases and vapors from the still to the heat interchanger, a pipe to bring only heavy tar from its receiver into indirect heat exchange relation with the gases and vapors in the heat interchanger, a vapor chamber, a pipe to convey the heated tar from the heat interchanger to the vapor chamber, a condenser to condense the vapors coming from the vapor chamber, and a pipe to convey residue from the vapor chamber to the still.
6. In connection with a coke oven battery, a gas collector main, means for cooling the gases in the main to produce heavy tar, a condenser for cooling the gases leaving the main to separate tarry oil, separate receivers connected with the collector main and condenser for the heavy tar and tarry oil respectively, a still, the only feeding means for the still being a pipe to convey heavy tar from this receiver to the still, a mixing tank, a pitch draw-off from the still leading to the mixing tank, and a pipe for conveying the tarry oil to the mixing tank.
7. In connection with a coke oven battery, a gas collector main, means for cooling the gases in the main to produce heavy tar, a condenser for cooling the gases leaving the main to separate tarry oil, separate receivers connected with the collector main and condenser for the heavy tar and tarry oil respectively, a still, the only feeding means for the still being a pipe to convey heavy tar from this receiver to the still, a mixing tank, a pitch draw-off from the still leading to the mixing tank, a pipe for conveying tarry oil to the mixing tank, a condenser to condense vapors coming from the still and produce a distillate, tar acid extraction apparatus, a pipe to convey the distillate to the extraction apparatus, and a pipe to convey neutral oil from this apparatus to the mixing tank.
